CLEANING MACHINE

Raymond C. Menendez, 184—55 Tudor Road,
Jamaica, N.Y.

Filed Oct. 4, 1955, Ser. No. 538,364

11 Claims. (Cl. 15—50)

The present invention relates to brushing and scrubbing machines characterized herein as cleaning machines of the type used for scrubbing or polishing floors, shampooing rugs and the like or performing similar operations and, more particularly, to an improved applicator head for performing the desired cleaning operations which head is constructed and arranged to dispense a liquid used in conjunction with such operations.

Heretofore, cleaning machines of such character have been employed but these were not entirely satisfactory because the liquid was not dispensed at a predetermined rate and the dispensed liquid was not uniformly distributed throughout the applicator means of the head.

Accordingly, an object of the present invention is to provide an improved applicator head for cleaning machines which overcomes the foregoing difficulties and disadvantages.

Another object is to provide such a head wherein the liquid used is dispensed at a metered rate.

Another object is to provide such a head wherein the liquid used is uniformly distributed throughout the applicator means of the head.

Another object is to provide such a head wherein the rate at which the liquid is dispensed can be adjusted to comply with requirements for particular cleaning operations.

A further object consists in the construction and arrangement of the head whereby the foregoing objects may be achieved in a simple and economical manner.

Other and further objects will be obvious upon an understanding of the illustrative embodiment about to be described, or will be indicated in the appended claims, and various advantages not referred to herein will occur to one skilled in the art upon employment of the invention in practice.

In accordance with the present invention, the foregoing objects are generally accomplished by providing a rotatable applicator head which comprises an outer chamber for dispensing the liquid adjacent the applicator means, an inner chamber serving as a reservoir for the liquid, and aperture means through which the liquid is adapted to be metered from the inner chamber to the outer chamber by centrifuging of the liquid upon rotation of the head.

A preferred embodiment of the invention has been chosen for purposes of illustration and description and is shown in the accompanying drawing, forming a part of the specification, wherein:

Fig. 1 is a perspective view illustrating a cleaning machine of the type adapted for utilizing the present invention in connection therewith.

Fig. 2 is an enlarged fragmentary view of the machine shown in Fig. 1, partly in elevation and partly in section.

Fig. 3 is a sectional view on a reduced scale taken along the line 3—3 on Fig. 2.

Fig. 4 is a sectional view on a reduced scale taken along the line 4—4 on Fig. 2.

2

Fig. 5 is a sectional view taken along the line 5—5 on Fig. 2.

Fig. 6 is an enlarged sectional view taken along the line 6—6 on Fig. 3.

Fig. 7 is a fragmentary plan view taken along the line 7—7 on Fig. 6.

Referring to the drawing in detail and more particularly to Figs. 1 and 2 thereof, a mobile cleaning machine is shown which generally comprises a frame 10, an electric motor 11 mounted on the frame, an applicator head 12 rotatably suspended by the frame and arranged for rotation by the motor, carriage means, such as a roller 14 for supporting the frame for movement across the surface to which the head is applied, and a handle 15 on the frame for moving the machine across such surface.

As shown in Figs. 2, 3 and 4, the head 12 comprises inner and outer basins, receptacles, shells, or generally cup-shaped sections 16 and 17, respectively, with the inner basin nested within and encased by the outer basin to provide a space therebetween. This is accomplished by providing the outer basin with an inwardly and preferably upwardly extending flange 18 and by providing the inner basin with an outwardly and preferably downwardly extending flange 19 adapted to rest on the flange 18 and thereby support the inner basin within the outer basin. As illustrated herein, the flange 18 is just below the lip of the outer basin and the flange 19 is at the lip of the inner basin.

A cover 20 is attached to the lip of the outer basin and is spaced from the lip of the inner basin. The cover is provided with a filling opening 21 which communicates with the inner basin and is normally closed by a plug 22.

The bottom of the outer basin 17 is formed with a plurality of spaced dispensing apertures 24 and has applicator means secured thereto adjacent these apertures, such as a plurality of brush tufts 25.

In the arrangement so far described, the inner basin 16 provides a chamber or reservoir for the liquid used in the cleaning operation, such as a soap or shampoo solution, a liquid wax or a volatile cleaning fluid, and the space between the basins formed by the side walls thereof and the flange 18 provides a passageway connected to apertures 24 for receiving liquid from the inner chamber, lathering or dispensing the liquid and conducting the liquid to the apertures 24.

When the head is rotated by the motor 11, the liquid in the inner chamber is centrifuged upwardly and outwardly and flows across the lip of the inner basin into the annular trough provided by the flanges. Thus, in accordance with the present invention, this liquid is metered from the inner chamber to the outer chamber, whereby the rate at which it is dispensed through the apertures 24 can be maintained at a desired uniform value. This is accomplished by providing the flanges 18 and 19 with one or more registering apertures 26. Four of such apertures, spaced equidistantly and circumferentially, are provided on each flange by way of example, and the flanges are arranged to maintain these apertures 26 in registry. The trough provided by the flanges 18 and 19 assures a steady supply of liquid to the apertures 26.

If desired, the outer chamber may be compartmented with at least one aperture 24 (but preferably a group of such apertures) serving as an outlet for each compartment, and one set of the apertures 26 serving as an inlet 65 for each compartment. This is accomplished by mounting radial ribs 27 between the inner and outer basins, four of such ribs being shown by way of example. These ribs may end short of the center of rotation of the basins, as shown, to provide baffles which permit communication between the compartments or may meet at such center to completely isolate each compartment.

By utilizing such ribs or baffles, the lathering or dispensing action is promoted, swirling of the liquid in the outer chamber is minimized whereby downward flow to the dispensing apertures is induced and the liquid is more evenly distributed through the applicator means.

As shown in Figs. 2 and 5, rotation of the head 12 by means of the motor 11 is effected through a slip clutch 30. As previously indicated herein, it is desirable to vary or adjust the rate at which the liquid is metered from the inner chamber to the outer chamber, because the rate at which the liquid is to be dispensed may vary with the particular liquid used or the operation to be performed. This is accomplished by resting the flange 19 on the flange 18 in a manner to permit slight rotative movement between the flanges, so that the effective opening provided by registering apertures 26 can be varied.

As shown in Figs. 6 and 7, such adjustment can be performed exteriorly of the head 12 by providing a short circumferential slot 31 in the cover 20 and securing an element to the inner basin, for example to its flange 19, which element has a portion 32 extending outwardly of the slot adapted for manual engagement.

From the foregoing description, it will be seen that the present invention provides a novel and practical applicator head for cleaning machines of the class described. The head is relatively simple in construction, is economical to manufacture, and can endure such vigorous use to which it may be subjected. The head is constructed and arranged so that the cover can be removed and the inner and outer basins can be taken apart for complete and thorough cleaning.

As various changes may be made in the form, construction, and arrangement of the parts herein, without departing from the spirit and scope of the invention and without sacrificing any of its advantages, it is to be understood that all matters are to be interpreted as illustrative and not in any limiting sense.

What is claimed is:

1. In a machine of the class described, a rotatable applicator head comprising a generally concave inner section providing a chamber for a liquid to be applied, a generally concave outer section encasing said inner section and spaced therefrom to provide a chamber between said sections, said sections being movable with respect to each other, a cover for said outer section, an annular flange on each of said inner and outer sections having registerable openings therein for metering liquid from the inner chamber to the outer chamber, and applicator means on the exterior of said outer section, said outer section having aperture means for dispensing liquid from the outer chamber.

2. An applicator head according to claim 1, wherein said flanges are constructed and arranged to adjust the effective area of said metering openings.

3. In a machine of the class described, a rotatable applicator head comprising an outer basin having at its upper rim an inwardly extending flange provided with aperture means, a cover for said outer basin, an inner basin within said outer basin and spaced therefrom and from said cover, said inner basin having at its upper rim an outwardly extending flange resting against said inwardly extending flange and being provided with aperture means adapted to register with said aperture means of said inwardly extending flange, and applicator means

on the exterior of said outer basin, said outer basin having openings in the bottom thereof.

4. An applicator head according to claim 3, wherein said flange on said outer basin extends upwardly and said flange on said inner basin extends downwardly.

5. An applicator head according to claim 3, wherein radial ribs are disposed between said inner and outer basins to provide baffled compartments therebetween each communicating with registering aperture means and at least one of said openings in the bottom of said outer basin.

6. An applicator head according to claim 3, wherein said outwardly extending flange is disposed on said inwardly extending flange for relative rotative movement between said flanges, whereby the effective opening provided by said registering aperture means can be adjusted.

7. An applicator head according to claim 5, wherein said cover has a slot and an element is secured to said outwardly extending flange and projects through said slot to provide means for effecting adjustment of said aperture means.

8. In a machine of the class described, a rotatable applicator head comprising an outer shell having an inwardly extending flange spaced adjacently from its rim and provided with a plurality of circumferentially spaced apertures, a cover for said outer shell, an inner shell within said outer shell and spaced therefrom having an outwardly extending flange at its rim disposed on said other flange for relative rotative movement between said flanges and provided with a plurality of apertures adapted to register with the apertures of said other flange, means on said inner shell and accessible exteriorly for adjusting the position of said inner shell to vary the effective opening provided by said registering apertures, and applicator means on the exterior of said outer shell, said outer shell having openings adjacent said applicator means.

9. An applicator head according to claim 8, including a normally closed filling opening for said inner shell.

10. An applicator head according to claim 8, wherein said flanges are inclined upwardly from the outer shell to the inner shell to provide an annular trough between said shells.

11. In a rotatable applicator, the combination with a motor and a brush rotated by said motor, of a reservoir adapted to be rotated by said motor and adapted to contain a supply of liquid therein, a laterally projecting flange at an upper edge of said reservoir having openings therein, means connected to the openings forming a passageway for said liquid between said reservoir and said brush, and means interconnecting said motor and said reservoir, whereby upon rotation of said reservoir by said motor the liquid is centrifuged through said openings along said passageway into said brush.
